CHECKING CABINET

Elmer W. Davis, Newton Center, Mass., assignor
to American Locker Company, Inc., Boston,
Mass., a corporation of Delaware

Application March 7, 1945, Serial No. 581,504

8 Claims. (Cl. 312—287)

1

This invention relates to checking cabinets and more especially to a novel cash box or bag distributing and receiving assembly for automatically serving the sales employees in department stores. The present procedure of manually distributing the required cash and equipment to the employees at the beginning of each day and of checking in the receipts at the end of the day creates two inefficient and confused bottle-necks of chaotic nature and so divides responsibility and fosters laxity that substantial losses, inaccuracies and confusion results. The primary object of my invention resides in the production of a novel cash box control service which will not only eliminate these objections and permit each employee to serve herself both morning and evening but will furthermore place each employee on her own responsibility and eliminate errors due to the inefficiency and carelessness of others.

My invention contemplates the employment of a cash container-distributing and receiving assembly embodying the use of cabinets each containing a plurality of individual employee compartments. The compartments are of uniform size and shape and in the preferred form of the invention each is adapted to receive a cash box of predetermined dimension to fit within the compartment. All compartments are open at the rear for free insertion and removal of the boxes by supervised clerks and the front of each compartment is provided with a closure door having a key controlled lock. A compartment, cash box and cooperating key are assigned to each sales employee who thereupon becomes personally responsible for the same.

The cash boxes are made up at night and placed in the compartments and each employee secures her box in the morning merely by using her key. The lock is constructed to retain the key when the compartment is in unlocked condition and, in accordance with my invention, the key and lock can be moved to the door locking position only when the cash box is in the compartment and the door closed, thereby preventing unauthorized locking of the door and removal of the key. At the end of the day each employee returns her cash box to its compartment and locks the door, taking the key with her. It will be apparent that in accordance with the invention the employee cannot lock the compartment door and take the key without first depositing the box in the compartment. The production of a cabinet embodying these novel features comprises a further object of the invention.

2

A record of absentees is essential and it will be apparent that the boxes remaining in the compartments after the opening hour in the morning provides such a record. Temporary substitute sales employees are assigned to these boxes and give receipts therefor as the boxes are handed out by the cashier. Each compartment lock is also provided with a meter which automatically records any tampering with the compartment aside from their use at the regular morning and evening periods. The production of a novel control service of this nature embodying the cash box distributing and receiving assembly herein described comprises a further object of the invention.

These and other features of the invention will be best understood and appreciated from the following description of preferred embodiments thereof selected for purposes of illustration and

20 shown in the accompanying drawings in which,

Fig. 1 is a fragmentary front elevation of an employee locker cabinet embodying my invention,

Fig. 2 is a vertical sectional view taken on line

2—2 of Fig. 1,

Fig. 3 is an enlarged front elevation of one of the cabinet compartments, partially broken away to show a portion of the lock mechanism,

Fig. 4 is a plan section taken on line 4—4 of Fig. 3,

Fig. 5 is a fragmentary view taken on line 5—5 of Fig. 3,

Fig. 6 is a plan sectional view through a compartment having a modified form of lock control,

Fig. 7 is a fragmentary rear face view illustrating a portion of the lock controlling mechanism,

Fig. 8 is a fragmentary view taken on line 8—8 of Fig. 9 and showing mechanism permitting movement of the lock bolt to door-locking position only when the door is fully closed, and

Fig. 9 is a plan view taken on line 9—9 of Fig. 8.

In Figs. 1 and 2 I have illustrated a fragmentary portion of a cabinet 10 embodying a bank of individual employee locker compartments 11 each adapted to receive a cash box 12 of a size to be received within the compartment. Each compartment is open at the rear and is provided with a closure door 14 at the front. The door is hinged at 15 and a spring 16 normally swings it to closed position. An opening knob 18 is carried by each door.

Each compartment is provided with a locking unit 20 of the nature shown in Patents 1,640,605 and 2,222,434 and adapted to be locked in place 50 in the compartment by a locking bolt 22. Each

locking unit 20 is provided with a locking bolt 22 of the nature shown in Patents 1,640,605 and 2,222,434 and adapted to be locked in place 55 in the compartment by a locking bolt 22. Each

such unit embodies a lock 24 having a bolt 26 for locking the door 14 in closed position. A counter meter 28 automatically records each closing movement of the lock 24, thereby recording any additional or abnormal locking of the compartment. Also cooperating with the lock 24 is an arm 30 (Fig. 7) pivoted at 32 and having a hook 34 on its free end adapted to cooperate with a notch 36 in the lock cylinder. A spring 38 normally swings the arm in a direction pulling the hook into the notch and thereby preventing rotation of the cylinder from the unlocked position to the door locking position. The arm 30 has a branch arm 40 provided with a finger 42 on its free end which swings with the arm 30. When no obstruction prevents such swinging movement, the hook 34 prevents rotation of the lock to the door locking position of Fig. 3.

As illustrated in Figs. 1-5, each compartment 11 is provided with a bottom plate or platform 44 supported at its rear end by bolts 45 above the bottom wall 43 of the compartment and having its forward end normally raised by springs 46 to the position illustrated in Fig. 2. A flat metal strip abutment 47 secured to the forward end of the plate 44 at its side edge extends upwardly to a position opposed to the finger 42 and is provided therein with a gap or opening 48 located opposite to the finger when the platform 44 is in its normal raised position, a solid portion of the strip being located opposite to the finger and providing an abutment therefor when the platform is depressed as illustrated in Figs. 3 and 5. When the cabinet is empty and in unlocked condition the hook 34 prevents rotation of the lock 24 to the door locking position and, as is common with locks of this nature, the key 51 can be removed only when the lock is in the door locking position of Fig. 3. When the employee deposits her cash box or bag in the cabinet gravity operating thereon depresses the plate 44 to the position of Fig. 3, wherein the strip 47 obstructs normal movement of the finger 42 and hook 34, thereby rendering the hook inoperative and permitting rotation of the lock 24 to the door locking position. Thus the abutment 47 is gravity operated through any weight placed on the platform 44 to a position permitting the lock to be moved to the door locking position. The upturned rear edge of the wall 43 forms a flange 50 which limits rearward movement of the box 12.

In Fig. 6, I have illustrated a modified form of the lock controlling mechanism, the compartment and lock being otherwise the same as in Figs. 1-5. In this construction an abutment 60 supported by a plurality of rods 62 is provided at the rear of each cabinet. Springs 64 normally move the abutment forwardly to a limit stop position permitted by heads 66 on the rods. The abutment is so located that the placing of the cash box 12 in the compartment and closing of the door 14 moves the abutment to its abnormal position, illustrated in Fig. 6. A flat metal vertical strip 68 is connected by a long horizontal strip 70 to the abutment 60 and is disposed forwardly of the finger 42 (shown in broken lines in Fig. 6) when the abutment is in its forward and normal position. When the abutment is forced to its rearward and abnormal position the strip 68 is disposed in opposed relation to the finger and forms an obstruction preventing normal movement of the finger and hook 34, thereby permitting rotation

of the lock to the door locking position illustrated in Fig. 3. As illustrated, the box is of such predetermined length that the placing of it in the compartment and closing the door must necessarily move the abutment to its abnormal position and permit locking of the door.

In accordance with my novel cash box control service, the cash boxes are made up at night and placed each in its respective compartment 11. Each employee retains her key and secures her box at the opening of the business day merely by using her key. The boxes remaining in the cabinet after the opening period automatically provide a record of absentee employees and can be cared for in any procedure desired. At the end of each day each employee returns her cash box to her compartment, locks the door and takes the key. It will be apparent that a double check on the proper return of the boxes is attained by the arrangement which prevents locking of the door and removing of the key before depositing the box in the compartment. The boxes are automatically placed in the pre-arranged order in the compartments as assigned and an accounting of the receipts can therefore proceed with greatest efficiency. It will be apparent that my novel system provides maximum efficiency both in the distribution of the boxes at the beginning of each day and in the accounting of the receipts at the end of the day and furthermore places the responsibility for each box directly on the employee.

It is desirable that the lock bolt 26 shall be movable to the door locking position of Fig. 3 only when the door is fully closed, and in Figs. 8 and 9 I have illustrated mechanism for automatically assuring this function. Pivoted on the wall 80 at 81 is a pendulum-like member 82 carrying a U-shape abutment plate 84 on its bottom end. The U-plate straddles the wall 80 and one portion is located in the path of movement of the flange 86 of the door 14. When the door is open the member 82 swings to its vertical position in which the plate 84 covers the bolt receiving opening 88 and prevents passage of the bolt 26 therethrough. Closing of the door pivots the plate to the position illustrated in Fig. 8 and in which position the opening 88 is unobstructed and the lock can be rotated to the door locking position.

It will now be apparent that my invention provides a checking cabinet together with associated means for preventing locking of the cabinet door unless and until the box or parcel is deposited in the cabinet. A preferred means for performing this function includes the latch 30 shown in Fig. 7 and having a finger 42 cooperating with the upright abutment 47 carried by the cabinet platform 44. Normally, the platform assumes a position disposing a gap or opening 48 in the abutment in alignment with the finger and permitting the finger and latch to function and prevent the door locking movement of the lock. However, when a box or parcel is deposited on the platform in the cabinet the plate 47 is depressed to the position shown in Fig. 5 in which it serves as a stop preventing movement of the finger and functioning of the latch 30. In Figs. 8 and 9 I have shown a modified construction eliminating the latch 30 and operating directly on the lock normally to prevent its rotation to door locking position. In this case the abutment 84, corresponding to the abutment 47, is mounted to move

into and out of the path of movement of the locking bolt and normally operates directly to prevent rotation of the lock to door locking position. As illustrated in the drawing the abutment 84 is pivoted at 81, normally hangs by gravity to the bolt obstructing position and is adapted to be moved by the door to non-obstructing position when the door is closed. These and other equivalent means can be employed in the invention to perform the function of preventing rotation of the lock to door locking position until the parcel is deposited in the cabinet and/or the door is closed.

Having thus disclosed my invention what I claim as new and desire to secure by Letters Patent of the United States is:

1. A cash box distributing and receiving assembly, comprising a cabinet embodying a plurality of independent compartments relatively disposed horizontally and vertically and each adapted to receive a cash box, a closure door at the front of each compartment, a key controlled lock for retaining the door in closed position, means cooperating with the lock and normally preventing its movement to the door locking position, and cooperating means for rendering the first named means inoperative when the cash box is in the compartment and the door closed.

2. A checking cabinet comprising walls providing a chamber, a closure door therefor, a key controlled lock for retaining the door in closed position, means cooperating with the lock and normally preventing its movement to the door locking position, a box of predetermined dimension adapted to be received within the chamber, and means located in the path of movement of the box when the box is being moved rearwardly in the chamber by closing movement of the door for moving the first named means to inoperative position.

3. A checking cabinet comprising walls providing a chamber, a closure door therefor, a key controlled lock including a locking bolt carried on said walls for retaining the door in closed position, means carried on said walls and normally in the path of movement of the bolt for preventing movement of the bolt to the door locking position when the door is open, and means located in the path of movement of the door for automatically moving the first named means to an abnormal position out of said path and permitting movement of the bolt to the door locking position when the door is moved to its closed position.

4. A checking cabinet comprising walls providing a chamber, a closure door therefor, a key controlled lock including a locking bolt carried by the cabinet and operative on the door for retaining the door in closed position, a pendulum-like member pivoted to the cabinet and normally hanging by gravity to a position obstructing movement of the bolt to the door locking position, and means located in the path of movement of the door for pivoting the mem-

ber to an abnormal position permitting movement of the bolt to the door locking position when the door is moved to its closed position.

5. A checking cabinet comprising walls providing a chamber, a closure door therefor, a key controlled lock having a locking bolt for retaining the door in closed position, a member in the chamber normally in a predetermined position and adapted to be moved to an abnormal position by an article deposited in the chamber, a latch and cooperating means normally operative to prevent rotation of the lock to the door locking position, and means cooperating with said member and the latch for rendering the latch inoperative when the member is in said abnormal position.

6. The assembly defined in claim 1 in which the last named means includes a movably mounted member in each compartment for receiving and supporting the cash box and an abutment associated with the member and adapted to be moved by weight of the box on the member for rendering the first named means inoperative when the box is in the compartment.

7. The assembly defined in claim 1 in which the last named means includes a movably mounted member disposed in each compartment in a normal position adapted to be engaged by the box and moved to an abnormal position when the box is fully disposed in the compartment and an abutment associated with the member and the first named means to render said means inoperative when the member is in the abnormal position.

8. A checking cabinet comprising walls providing a chamber, a closure door therefor, a key controlled lock having a locking bolt for retaining the door in closed position, a platform in the chamber adapted to receive thereonto an article deposited in the chamber, means operative on the lock normally to prevent movement of the bolt to door-locking position, and gravity operated means cooperating with the platform and the first named means for rendering the first named means abnormally inoperative when said article is deposited onto the platform.

ELMER W. DAVIS.
